UNITED STATES PATENT OFFICE.

GEORGE W. HYSER, OF MINNEAPOLIS, MINNESOTA.

DEAD FRONT SAFETY PANEL

Application filed January 3, 1921. Serial No. 434,647.

To all whom it may concern:

Be it known that I, GEORGE W. HYSER, a citizen of the United States, resident of Minneapolis, county of Hennepin, State of Minnesota, have invented certain new and useful Improvements in Dead Front Safety Panels, of which the following is a specification.

My invention relates to cabinets wherein circuit switches, fuse cups and other electric connections are mounted and the object of the invention is to provide a construction for the interior of the cabinet which will eliminate all danger of injury to an attendant through contact with the live conductors or connections.

A further object is to provide a dead front panel for a cabinet of the class described which will be ornamental and of more pleasing appearance than the panels as ordinarily constructed.

A further object is to eliminate the use of fuse cups and switches of special construction and also the polishing and finishing of all bus and branch bars.

A further and particular object is to provide a construction which will make it possible to remove either fuse cup or switch from the panel without disturbing any of the steel plates, bus bars, or any other part of the equipment, and, further, to provide a panel of simple inexpensive construction and one which can not be deranged or inadvertently damaged by a person unfamiliar with devices of this kind.

The invention consists generally in various constructions and combinations, all as hereinafter described and particularly pointed out in the claims.

In the accompanying drawings forming part of this specification,

Figure 1 is a front elevation of a portion of a cabinet with my invention embodied therein;

Figure 2 is a horizontal sectional view on the line 2—2 of Figure 1.

Figure 3 is a rear view of the panel removed from the cabinet to show the bus bar connection thereon;

Figure 4 is a cross sectional view on the line 4—4 of Figure 3;

Figure 5 is a similar view on the line 5—5 of Figure 3.

In the drawings, 2 represents the rear wall of the cabinet and 3 the side walls formed preferably by folding outwardly the edges

of the sheet steel plate of which the rear wall 2 is composed and 4 is the front of the cabinet, secured by suitable means to the inwardly turned flanged edges 5 of the side walls. In this style of cabinet front I provide a single door 6 through which access is had to the interior of the cabinet and the mechanism contained therein. When switches are employed in the circuit two doors will be provided in the front of the cabinet. This arrangement of doors, however, is not novel, and I make no claim to such construction herein. 7 represents the sheet of insulating material which I prefer to place against the rear wall of the cabinet and in the rear of the bus bars and other apparatus which will presently be described in detail. 8 is a yoke having end portions 9 secured to the rear wall of the cabinet by suitable means, such as screws 10 and on this yoke the insulating plate or element 11, preferably of slate, usually used in cabinets of this kind, is mounted. A space 12 is provided between the plate 11 and the rear wall of the cabinet and in this space I arrange the potential bus bars 13 separated by air gaps from the walls of the cabinet and from the yoke 8. The neutral bus bar 13^a is arranged between the other bars and seated on a branch bar 13^b which connects the opposite fuse cups and is preferably seated on the back of the insulating element. Ordinarily these bus bars are arranged in front of the plate whereon the fuse cups are mounted and a steel plate is arranged in front of the bus bars. Such construction is objectionable, as it increases the expense of the device; the steel plate, while normally dead, is liable to become charged from one of the switches in the rear of the plate so that an operator or attendant may receive a severe shock while working around the cabinet.

By locating the bus bars in the rear of the plate 11 where they cannot be seen, or reached by the ordinary observer or attendant, I eliminate all danger of charging any of the conductors with which the hands of an attendant may come in contact and furthermore, the bus bars are not particularly ornamental and the appearance of the cabinet is greatly enhanced by concealing them in the rear of the insulating plate of slate 11.

The outer bus bars 13 are secured to the back of the plate 11 by means of suitable screws 14, and are preferably spaced therefrom by suitable spacing collars 14^a as shown

in Figure 4. These two bus bars are electrically connected to the fuse cups 16 (of ordinary construction) by means of the screws 14 which pass through the plate 11 and have their heads seated in the cups, as shown. The central bus bar 13^a is electrically connected to the complementary fuse cups 16^a by means of the branch bars 13^b and screws 14^b as shown in Fig. 5. A connecting screw 15 is also provided in each fuse cup, and these screws have their lower ends suitably secured to a series of connecting bars 17 which have their outer ends in electrical connection with the binding posts 18. In Fig. 3, there is shown a panel having four branch circuits, each circuit comprising two fuse cups 16 and 16^a. Thus, it will readily be seen that when fuse plugs are inserted in the cups 16 and 16^a of a circuit, such circuit will be closed between the bus bars and binding posts 18. A wall of either slate or steel 19 encircles the fuse cups in this type of panel and extends outwardly from the plate 11 to a point near the front wall of the cabinet and prevents the attendant from inserting his hand into the space between the plate 11 and the front of the cabinet and coming in contact with the terminals 18 or with any other charged part of the apparatus. When switches are employed in the circuits the insulating wall incloses the switches only.

In various ways the details of construction herein shown and described may be modified and still be within the scope of my invention, the essential feature of which consists in providing the insulating plate in front of the bus and bars thereby protecting the person working around the cabinet from injury.

I claim as my invention:

1. The combination, with a cabinet, of an insulating plate mounted therein and spaced from the rear wall of the cabinet, bus bars arranged in the space between said rear wall and said insulating plate, fuse cups mounted on the front of said insulating

plate and in circuit with said bus bars, terminals for said bus bars mounted in the outer portions of said insulating plate, and an insulating wall encircling said fuse cups and separating them from said terminals. 50

2. The combination, with a cabinet, of an insulating plate mounted therein, bus bars arranged in the rear of said insulating plate and normally concealed thereby, terminals for said bus bars mounted in said insulating plate, fuse cups mounted on the front of said insulating plate and in circuit with said bus bars and a wall within said cabinet interposed between said terminals and said fuse cups and closing the gap around said cups and between them and said terminals. 55 60

3. The combination with a cabinet having a front wall and a door opening therein and a door therefor, of an insulating element mounted in said cabinet in the rear of said door opening and opposite the same, bus bars mounted in the rear of said insulating element, terminals therefor mounted on said insulating element, fuse cups mounted on said insulating element and connected with said bus bars, and means interposed between said insulating element and the edge of said front wall around said door opening and guarding said terminals and preventing the hand reaching through said door opening from contacting with said terminals. 65 70 75

4. The combination, with a cabinet having a front wall and a door opening therein and door therefor, of an insulating plate mounted in said cabinet in the rear of said door opening and opposite the same, bus bars mounted in the rear of said plate, terminals therefor mounted on said plate, fuse cups mounted on said plate and connected with said bus bars and a wall separating said terminals from said fuse cups and projecting outwardly from said plate to a point near said door opening and preventing access to said terminals through said opening. 80 85 90

In witness whereof, I have hereunto set my hand this 29th day of December, 1920.

GEO. W. HYSER.
